US00D809545S

(12) **United States Design Patent** (10) Patent No.: **US D809,545 S**
(45) Date of Patent: **** Feb. 6, 2018**

(54) **DISPLAY SCREEN WITH GRAPHICAL USER INTERFACE**

(71) Applicant: **Hitachi, Ltd.**, Chiyoda-ku, Tokyo (JP)

(72) Inventors: **Masahide Ban**, Tokyo (JP); **Kazuhiro Ikegaya**, Tokyo (JP); **Yukinobu Maruyama**, Tokyo (JP); **Shotaro Tamayama**, Tokyo (JP); **Chiaki Hirai**, Tokyo (JP)

(73) Assignee: **Hitachi, Ltd.**, Tokyo (JP)

(**) Term: **15 Years**

(21) Appl. No.: **29/578,272**

(22) Filed: **Sep. 20, 2016**

(30) **Foreign Application Priority Data**

Mar. 24, 2016 (JP) 2016-006347

(51) **LOC (11) Cl.** **14-04**

(52) **U.S. Cl.**

(57) **CLAIM**

The ornamental design for a display screen with graphical user interface, as shown and described.

DESCRIPTION

The file of this patent contains a least one drawing executed in color. Copies of this patent with color drawings will be provided by the Office upon request and payment of necessary fee.

The FIGURE is a front view of a display screen with graphical user interface showing our new design.

The outer light gray rectangular border and oval button showing the display screen are included for the purposes of illustrating a portion of the article and form no part of the claimed design.
